UNITED STATES PATENT OFFICE

161,262

BEDSIDE CABINET COMMODE

William S. Horn, Fort Worth, Tex.

Application May 19, 1950, Serial No. 10,040

Term of patent 14 years

(Cl. D4—5)

To all whom it may concern:

Be it known that I, William S. Horn, a citizen of the United States of America, residing at Fort Worth, in the county of Tarrant and State of Texas, have invented a new, original, and ornamental Design for a Bedside Cabinet Commode, of which the following is a specification, reference being had to the accompanying drawing, forming part thereof.

Figure 1 is a perspective illustration of a bedside cabinet commode, embodying my new design shown from the right side thereof.

Figure 2 is a left side perspective illustration of the cabinet showing the top raised, and

Figure 3 is a plan view of the cabinet commode.

I claim:

The ornamental design for a bedside cabinet commode, substantially as shown.

WILLIAM S. HORN.
